UNITED STATES PATENT OFFICE

HERMAN D. OSGOOD, OF SOMERVILLE, MASSACHUSETTS, ASSIGNOR OF ONE-THIRD HIS RIGHT TO JAMES M. OSGOOD, OF SAME PLACE.

IMPROVEMENT IN WATER-PROOF BOOTS AND SHOES.

Specification forming part of Letters Patent No. 177,656, dated May 23, 1876; application filed April 19, 1876.

To all whom it may concern:

Be it known that I, HERMAN D. OSGOOD, of Somerville, in the county of Middlesex and State of Massachusetts, have invented a new and valuable Improvement in Making Boots and Shoes; and I do hereby declare that the following is a full, clear, and exact description thereof, reference being had to the accompanying drawing, and to the letters of reference marked thereon.

The object of this invention is to render boots and shoes entirely water-tight. Of course, it is well known that the principal place at which water finds entrance is just over the sole, between it and the upper. I have, therefore, to obviate this difficulty, placed a sandal-shaped and very thin rubber piece, made whole, without seam, into the shoe during the process of manufacture. Its position in the shoe is between the outer and inner sole, and extending up for a short distance between the lining and upper. The shape of my device, allowing it to extend up around the sides, heel, and toe of the shoe, prevents the entrance of the water between the sole and upper, and renders it greatly superior to an ordinary rubber sole.

In the accompanying illustration, Figure 1 represents a portion of a shoe, with a piece broken out to show the position of the water-proof protector. Fig. 2 is a view of my water-proof device or protector detached from a shoe. Fig. 3 is a longitudinal vertical section of a shoe provided with the device.

Similar letters of reference indicate corresponding parts.

a represents the shoe-upper; *b*, the lining, while extending up between them is the water-proof protector *c*. This is well shown in

Fig. 1, and also by broken lines in Fig. 3. The shape of the protector is seen in Fig. 2. *d* in Fig. 3 represents the inner sole, and the broken line *e* the outer sole, while the black line *c* is the rubber protector.

This protector may be slipped over the last while the shoe is in process of making, and the upper fastened over it with perfect ease. If that part next to the sole *d* need any protection, a piece of cotton or other material may be pasted on the under side.

Any water-proof material may be used in place of rubber. Its sides may be higher or lower than shown in the drawing, as deemed most practicable.

It will be readily seen that by means of this device the boot or shoe to which it is applied will be rendered perfectly tight, not only at the sole, but at the sides and between the sole and upper, where the water is most likely to ooze in.

The sides and toe of the rubber protector may be covered with cloth, if desired, in order to protect the rubber from wear in case of breakage in the leather.

Having thus fully described my invention, what I claim, and desire to secure by Letters Patent, is—

In the manufacture of water-proof boots and shoes, the combination of the intermediate seamless upper and sole, of water-proof material, with the shoe-upper, lining, and soles, all arranged substantially as and for the purpose hereinbefore set forth.

HERMAN D. OSGOOD.
